K. KRAMP.
DOOR AND THE LIKE CHECKING DEVICE,
APPLICATION FILED FEB. 23, 1910.

969,882.

Patented Sept. 13, 1910.

Karl Kramp

UNITED STATES PATENT OFFICE.

KARL KRAMP, OF WUSSEKEN, NEAR BORTUCHEN, GERMANY.

DOOR AND THE LIKE CHECKING DEVICE.

969,882.

Specification of Letters Patent. Patented Sept. 13, 1910.

Application filed February 23, 1910. Serial No. 545,469.

To all whom it may concern:

Be it known that I, KARL KRAMP, a subject of the Emperor of Germany, residing at Wusseken, near Bortuchen, district of 5 Bütow, Pommerania, Germany, have invented certain Improvements in Door and the Like Checking Devices, of which the following is a specification.

My invention relates to a door and the 10 like checking device which is adapted to be actuated by the air-pressure, incurred by the forcible closing of the door, so as to form a resilient abutment for the same, absorbing the shock and deadening the noise.

15 The invention is illustrated by way of example in the accompanying drawing, Figures 1 and 2 representing side views of the device, partly in section, in inoperated and operated position respectively, Fig. 3, a 20 front view in cross-section along line A—B of Fig. 1, Fig. 4, a cross-section along line C—D of Fig. 1, and Fig. 5, a perspective view of one of the parts.

25 Two parallel plates *a* are connected by means of stay-bolts *b* or the like in any suitable manner. Between said plates a buffer *c* is slidably arranged and firmly guided. In the example shown the buffer is provided 30 with a dovetailed groove *d* and is adapted to slide by means of the same on a corresponding rib *e* connected to one of the plates. The buffer *c* is pressed outward by a helical spring *f* which is guided on a pin *h*, the latter being admitted in an aperture 35 in the buffer. A collar *g* on the pin can be adjusted for regulating the pressure of the spring. The buffer *c* is fitted on one side with a lug *n* and on the other side with a stop *p*, of which the latter limits its outward 40 movement. The plates *a* are further adapted to receive a V-shaped blade-spring between them. The members of said spring are parallel for a distance so as to form a 45 guide-way by means of which the spring is slidably mounted on a bolt *k*. A lock-spring *l* bears with its free end against the lower part of the spring *i* and presses it against the bolt. One member of the spring *i* is 50 weaker than the other and has an abutment in the form of a bolt *m*, and the other member rests against a lever *o* which is pivoted with its lower end to the plates *a* and which fills up the space between the front edges of 55 the latter. On the outer end of the lever *o* an outward bend is provided. At a slight

inward pressure on the lever *o* the weak member of the spring *i* yields whereby the other member is turned into the route of the lug *n* of the buffer *c* so as to be engaged by the latter. 60

The device is mounted in the door-casing, preferably near the lock, and is arranged so that the buffer *c* is depressed by the door when the latter is closed.

At a slow closing of the door the buffer 65 is easily depressed against the opposition of the spring *f*. Should the door be forcibly closed, however, the draft created thereby will actuate the lever *o* so that the spring *i* is turned, in the above described 70 manner into the route of the lug *n*. When the door depresses the buffer *c*, therefore, the latter is checked by the spring *i* which is pressed down on the bolt *k* against the 75 opposition of the spring *l*. The shock is absorbed by the springs and no noise is produced.

The recess for the door in the door-casing may in addition be lined with a strip of 80 felt, rubber, or the like, having the same color as the casing. The buffer *c* is preferably provided with a rubber front.

The mechanism may also be arranged in the lock and the construction of the parts may be varied without departing from the 85 spirit of the invention.

I claim:—

1. A device for checking doors and the like, comprising a buffer slidably arranged in the door-casing, a spring normally out 90 of engagement with said buffer, and a lever adapted, when the door is forcibly closed, to be actuated by the draft created by such closing so as to turn the spring into engagement with the buffer, the latter then 95 forming a resilient abutment for the door, substantially as and for the purpose set forth.

2. A device for checking doors and the like, comprising a buffer slidably guided between two plates mounted in the door-casing, a helical spring tending to hold the buffer in projecting position so as to be depressed by the door when closed, a lug on 100 the lower side of the buffer, a lever pivoted between the front edges of the plates and adapted to be pressed inward by the draft created when the door is forcibly closed, a V-shaped spring slidably guided on a 105 transverse bolt and pressed against the same 110

by a lock-spring, one member of the V-shaped spring being weak and bearing against a stay-bolt, the other member bearing against said lever so as to be turned by the same, when the latter is actuated by the draft, into engagement with the lug on the buffer, the latter then forming a resilient

abutment for the door, substantially as and for the purpose set forth.

KARL KRAMP.
